UNITED STATES PATENT OFFICE

94,119

DESIGN FOR A DOUGHNUT CUTTER

Homer Dady, Indianapolis, Ind.

Application August 9, 1934, Serial No. 52,881

Term of patent 3½ years

To all whom it may concern:

Be it known that I, Homer Dady, a citizen of the United States, residing at Indianapolis, in the county of Marion and State of Indiana, have invented a new, original, and ornamental Design for a Doughnut Cutter, of which the following is a specification, reference being had to the accompanying drawing, forming part thereof.

I claim:—

The ornamental design for a doughnut cutter as shown.

HOMER DADY.
